[57] **CLAIM**

The ornamental design for a magnetic card accessed
information terminal, as shown and described.

DESCRIPTION

FIG. 1 is a front elevational view of a magnetic card
accessed information terminal showing my new design;
FIG. 2 is a right side elevational view thereof, the left
side being a mirror image of FIG. 2;

FIG. 3 is a top, front view thereof, looking directly at
the inclined display, keyboard reader surface;

FIG. 4 is a bottom plan view thereof.
The back is plain and unornamented.

FIG. 2

FIG. 1

FIG. 4

FIG. 3
